Primary Examiner — Cynthia R Underwood

(57) **CLAIM**

The ornamental design for a dish as shown and described.

DESCRIPTION

1. Dish

2. Dish

1.1 : Perspective

1.2 : Top

2.1 : Perspective

2.2 : Top

The subject of this design is a dish. The dish is elliptical and has uniform projections at both ends that form the handles. The outside of the plate is covered with lines parallel to the base in different shades with parallel indentations.
